UNITED STATES PATENT OFFICE

150,665

DESIGN FOR A HELICOPTER

Arthur M. Young and Mancer H. Gleason, Buffalo, N. Y., assignors to Bell Aircraft Corporation, Wheatfield, N. Y.

Application November 14, 1946, Serial No. 134,774

Term of patent 14 years

(Cl. D71—1)

To all whom it may concern:

Be it known that we, Arthur M. Young and Mancer H. Gleason, citizens of the United States, residing at Buffalo in the county of Erie and State of New York, have invented a new, original, and ornamental Design for Helicopter, of which the following is a specification, reference being had to the accompanying drawing, forming part thereof.

Fig. 1 is a top plan view of a helicopter, showing our design;

Fig. 2 is a side elevational view thereof; and

Fig. 3 is a front end elevational view thereof.

The characteristic features of our design reside in the portions shown by means of full lines in the drawing.

We claim:

The ornamental design for a helicopter, as shown and described.

ARTHUR M. YOUNG.
MANCER H. GLEASON,
